UNITED STATES PATENT OFFICE.

GEORGE H. FAHRENBRUCH AND FRANK HOLADA, OF OMAHA, NEBRASKA.

Brake-Beam Fulcrum.

1,262,933.

Specification of Letters Patent. Patented Apr. 16, 1918.

Application filed December 7, 1917. Serial No. 205,961.

To all whom it may concern:

Be it known that we, GEORGE H. FAHREN-
BRUCH and FRANK HOLADA, citizens of the
United States, residing at Omaha, in the
5 county of Douglas and State of Nebraska,
have invented certain new and useful Im-
provements in Brake-Beam Fulcrums, of
which the following is a specification.

Our invention relates to a new and useful
10 improvement in brake beam fulcrums often
spoken of as strut or brake lever posts.

An object of our invention is to so con-
struct the fulcrum or post so that it may be
quickly changed from a right to a left one
15 or vice versa, to accommodate the brake
lever operated from either side.

Another important object of our inven-
tion is to so construct the fulcrum that in-
stead of passing the ordinary pin there-
20 through to hold the same in the post, a pin
is cut to a proper length which may be
placed through the brake lever, which pin
acts as lugs which are in turn placed in the
passageway provided in the fulcrum so that
25 it is impossible for the pin to accidentally
drop from the same, thus preventing the
brake lever from being accidentally disen-
gaged from the fulcrum post.

As is well known in the art the ordinary
30 pins work or drop out of the brake lever and
fulcrum allowing the brake rigging to be-
come disarranged and often thereby causing
serious accidents.

Still other objects of our invention are to
35 provide a fulcrum post that may be quickly
changed from left to right and in which may
be used a brake lever with a shortened pin;
but at the same time if it is desired to use
the old form of pin and cotter key it may
40 be done by simply drilling one hole in the
post at the end of the passage in said post.

With these and other objects in view our
invention consists in certain new and novel
45 constructions and combinations of parts as
will be hereinafter more fully described and
pointed out in the claims.

In the drawings forming a part hereof
wherein like numerals designate correspond-
ing parts,

50 Figure 1 is a plan view of an ordinary
brake beam with our improved fulcrum post
and lever in one of its positions.

Fig. 2 is a sectional view taken on line
2-2 of Fig. 1.

55 Fig. 3 is an end elevation but having the
face with a slot turned to the front.

Fig. 4 is a sectional view taken on line
4-4 of Fig. 3.

Fig. 5 is an end view showing the trans-
verse slotted portions, and

Fig. 6 is a sectional view of a slight modi-
fication, the section being taken in the same
position as Fig. 2.

Referring now to the drawings, we have
shown a conventional brake beam comprising
the compression member 1 of ordinary
channel shaped material and a tension mem-
ber 2. This tension member is shown as a
round rod, but it is to be understood that
a flat bar may be just as easily accommo-
dated.

Our invention resides in the fulcrum or
strut or brake lever post 3 which is pref-
erably cast in one solid piece, the inner end
or base 4 being rectangular in shape, the
75 middle portion 5 being also rectangular in
shape but the surfaces disposed at acute
angles with relation to the base 4, while the
outer end portion 6 is rounded as clearly
shown in Fig. 3.

Transverse grooves 7 and 8 are also pro-
vided on the outer end of the fulcrum post 3
to accommodate the tension member 2, that
is, the tension member 2 will be in one of the
grooves when the fulcrum is in one position
and in the other when the fulcrum is turned
to its other position.

Referring again to the base of the ful-
crum, 3, it is to be noticed that it is provided
with four grooves 9 disposed about cen-
trally of the faces and from one end of the
same to the other. These grooves are not
necessarily of much depth as clearly seen in
the drawings, their function being to partly
receive the rivets 10 that are passed
95 through the compression member 1 to
tightly hold the fulcrum post 3 in its set
position, and it will be noticed that only
two opposite grooves are in use at the one
time depending on the position of the ful-
crum post 3. Two bands 11 are shown
100 which partly encircle the channel beam or
compression member through the ends of
which are passed the rivets 10, which bands
are to help strengthen the beam and also
help hold the fulcrum post in place.

Before describing the other features of the
invention it might here be mentioned that
all that is necessary to change the position of
the post from one accommodating a left
110 hand rigging to one to accommodate a right
hand rigging, is to cut one of the rivets 10,

knock the fulcrum out of its position from the rear and shift it 90° ; or in other words, turn it to the right so that the faces of the base 4 which were formerly the top and bottom faces become the two side faces and replace a new rivet. These rivets now will fit within the grooves that occupy the vertical position and the post is now set to accommodate the brake lever which is operated from a right hand position.

This is a comparatively simple matter as it is not necessary to disarrange the brake beam in any way or loosen the tension member 2, as the post is easily slipped into place from the rear.

From this it will be seen that if it is desired to use the brake beam with the left hand rigging, the fulcrum post is set as clearly shown in Fig. 1, while if it is desired to be used with a car having a right hand rigging, one rivet only is cut away, the post revolved to the right so that the slot in the same is now on the right side, the necessary rivet is again placed in the position and the brake beam may now be used to accommodate a right hand brake rigging.

Referring now to the middle portion 5 of the fulcrum, it will be noticed that a slot is formed therein passing completely through the two opposite faces. This slot 12 is for the reception of the brake lever 13 which is fulcrumed in the post or strut 3. Extending transversely of this slot 12 and near the upper end are the cut out portions 14 which then curve downwardly as at 15 and then inwardly as at 16; in other words forming substantially an ogee curve. These cut out portions are, of course, on the inner surface of the slotted portion and the walls thereof guide the brake lever 13 to its final position, that is, the pin forming the lugs 17 in the brake lever 13 when passed in the cut out portion 14 will be guided downwardly and inwardly, and furthermore the lugs 17 will hold the pivot against the walls at 16.

With this construction it will be impossible for the brake lever to drop clear from the slot 12, as to remove the lever the pin forming the lugs 17 on the same will have to be moved backward following substantially the ogee curve.

Referring now for the moment to the modification shown in Fig. 6—supposing it is desired to use our improved post with an ordinary brake lever, all that is necessary is to drill a hole at 15 in the post at the end of the cut out portion as at 16 and pass the pin or bolt 20 through the base and the lever 21.

It will therefore be seen that although our post is primarily designed for use with a shortened pin, still should it be desired to use the ordinary form of lever and pin it may be done by simply drilling one hole 65 through the fulcrum post and passing the

ordinary pin or bolt through the same to hold the lever in its set position.

From the foregoing it will be seen that with our improved invention the fulcrum post may be used as either a right or left hand one, may be used with a certain form of short pin wherein it is impossible for the same to become accidentally removed, or, if the necessity arises, it may be used with the ordinary form of retaining pin now in use.

Having thus described our invention, what we claim as new and desire to secure by Letters Patent, is:

1. A brake beam fulcrum having a rectangular shaped base and angularly disposed remaining portion, said remaining portion provided with a slot therein for the reception of a brake lever and transverse passageways formed at the outer end of said post.

2. A brake beam fulcrum having a rectangular base, the four sides of said base being each provided with a groove therein extending across the face for the reception of retaining members, a central portion having a plurality of faces, said central portion having a slot extending completely through the same for the reception of a brake lever, and transverse passageways at the end of the fulcrum to accommodate a tension member.

3. A brake beam fulcrum adapted to be changed from a left to right position and vice versa, comprising a base, a central portion provided with a slot for the reception of a brake lever, the said slotted portion provided with cut out portions for guiding and retaining the brake lever in position.

4. A brake beam fulcrum adapted to be set in both a right and left hand position, a central portion of said fulcrum being slotted at an angle to a horizontal line, a tortuous guideway formed on the inner surface of the slotted portion to position a brake lever when placed in the slotted portion of the fulcrum, and the outer end of said post provided with transverse passageways.

5. A brake beam fulcrum in combination with a brake lever provided with lugs on its opposite faces, said post having a rectangular base provided with grooves on its side faces for the reception of retaining members, a rectangular central portion, the faces of the same disposed at an angle to the faces of the base, the said central portion provided with a slot extending through from one face to the other, said slot being also disposed at an angle to the faces of the base, the inner walls of the slotted portion having formed therein a cut out portion substantially in the form of an ogee curve and adapted to guide the lugs on the brake lever when said brake lever is inserted in the slotted portion.

6. In combination with a brake beam and
brake lever having lugs thereon, a right and
left hand fulcrum post fitting within the
compression member of said brake beam,
5 said fulcrum having a rectangular base pro-
vided with grooves therein, retaining means
passing through said compression members
and fitting within said grooves for holding
the fulcrum in its set position, said post be-
10 ing angularly slotted for the reception of
the brake lever, said base also having a

curved passageway formed on the inner
walls of the slotted portion for guiding and
retaining the said brake lever when placed
in said post, the outer end of said post hav-
15 ing two angularly disposed passageways for
the reception of a tension member.

In testimony whereof we affix our signa-
tures.

GEORGE H. FAHRENBRUCH.
FRANK HOLADA.
